UNITED STATES PATENT OFFICE.

THOMAS CARMICHAEL AND JOHN E. BOWLIN, OF FORT BRAGG, CALIFORNIA.

SAWMILL SETWORK.

Application filed March 29, 1926. Serial No. 98,249.

This invention relates to improvements in set works for use in connection with saw mill carriages in adjusting the knees or head blocks for predetermined distances toward or away from the saw blade.

The general object of the invention is to provide an apparatus of simple construction and requiring but a minimum of skill to operate in the setting thereof, to the end that the knees or head blocks of a saw mill carriage may be expeditiously adjusted in required spaced relation to the saw.

A further object is the provision of a construction wherein the knees or head blocks of a saw carriage may be expeditiously and accurately adjusted so that the saw will cut a log or cant to any of the usual commercial dimensions, and this without requiring any but the ordinary manipulation of the adjusting screws of the head blocks or knees.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a side elevation showing a portion of a sawmill carriage and the device of this invention in use;

Figure 2 is an enlarged detail side elevation of the complete invention with parts thereof broken away to disclose the construction and relation of other parts;

Figure 3 is a plan of Figure 2 on a slightly reduced scale;

Figure 4 is a detail cross-section on the line 4—4 of Figure 3, looking in the direction of the arrows;

Figure 5 is a sectional plan on the line 5—5 of Figure 4, looking in the direction of the arrows; the parts shown, however, being on a slightly enlarged scale with respect to the scale of Figure 4;

Figure 6 is a sectional detail taken through the recessed portion of the plate, showing the stop and the toothed wheel in side elevation and the frame in end elevation; and

Figure 7 is a view similar to Figure 6, except that the frame is shown in perspective.

In the drawings, 5 indicates the upright stop shaft which is journaled in bearings 7

of an upright frame 8 disposed upon the saw carriage 9, the said shaft having at its lower end a bevel gear 10 which meshes with a bevel gear 11 rigidly secured on a shaft 12 which forms part of the mechanism for adjusting the knees 13. These parts are all of well known construction.

14 is a horizontally disposed plate having a central opening receiving the upper end portion of stop shaft 5 and fixedly secured against rotation with the shaft 5. For purposes of illustration I have shown plate 14 as being secured to upright frame 8. Plate 14 may have any desired peripheral contour and, in the present instance, I have shown it as being substantially circular and provided with a vertical open ended recess 15 in which a two-ended stop 16 is arranged to oscillate or rock in a vertical plane. 17 is a rock shaft with its opposite end portions journaled in bearings 18 and 19 depending from the lower face of plate 14, and suitably rigidly secured thereto as by bolts 20.

An operating handle 21 is rigidly secured to a projecting end portion of rock shaft 17, so that the stop 16 may be rocked or turned in either direction when the handle 21 is manipulated. The upper end of the stop 16 is disposed substantially in a plane with the upper face of the plate 14 and nicely fits within the upper end of recess 15, so that when handle 21 is turned in one direction, one corner of the stop will be projected above the upper face of the plate, and the opposite corner moved downwardly, the said opposite corner, however, is projectable above the surface of the plate when the handle is turned in the required direction.

22 is a toothed wheel keyed or otherwise fixedly secured to shaft 5 and located above and in spaced relation to plate 14. In the construction illustrated, it is assumed that the pitch of the threads of the adjusting screws 23 is such that these screws will adjust the head blocks for a distance of approximately four inches in each rotation of the gearing connection 24 between the screws and the shaft 5, and likewise the shaft 5 will also turn at the same speed as the screws 23. It may be further assumed as an illustration that toothed wheel 22 is provided with one hundred and twenty teeth so that a movement of the gear wheel to the extent of one tooth would effect an adjustment of the screws 23 for a distance of one-thirtieth of an inch.

A horizontally disposed swinging frame 25 embraces toothed wheel 22 and has its upper side 26 and lower side 27 provided at their inner end portions with alining openings for the loose reception of the upper end portion of shaft 5. A horizontally disposed pawl 28 is slidably fitted between the sides 26 and 27 and is actuated by a link 29 to engage and disengage the toothed wheel 22.

In the construction shown the inner end of the pawl conforms to the curvature of the wheel and is provided with a plurality of teeth 30 adapted to interfit with the teeth of the wheel 22. The link is disposed with one end in a recess 31 in the outer end of the pawl and supported therein by a pin 32. The outer end of the link is connected to a pin 33 extending between a pair of disks 34 which are eccentrically secured to a shaft 35 which is disposed transversely of the outer end portion of the frame and journaled in the opposite side walls 36 thereof. An operating handle 37 is secured to a projecting end portion of shaft 35 and operates when rocked to oscillate the link 29 and thereby engage and disengage the pawl from the wheel 22. It will be noted that the pins 33 and 35 are disposed diametrically opposite and that when pawl 28 is engaged with wheel 22, pins 32, 33 and 35 are dead centered so as to provide against accidental displacement of pawl 28 from the wheel 22.

The marginal portion of the upper face of plate 14 is provided with a circular scale of inches, the scale being equally divided into four main divisions representing from one to four inches, and each division is subdivided into sixteenths. Any suitable means may be provided for indicating the divisions of the scale, such as a pointer 38 carried by the frame 25. It will be noted that the frame 25 extends radially of plate 14 and beyond stop 16 so that one of the ends of the stop projecting above the surface of the plate extends into the path of movement of the frame and thereby operates to limit movement of the frame in one direction beyond the zero point of the scale.

A spring pressed latch bolt 39 is disposed in a transverse recess in the plate and is yieldingly held within either of a pair of lateral detents 40 in stop 16. A compression spring 41 is confined between the head of the latch bolt and a plug 42 screwed into the recess. The latch bolt operates to hold the stop against accidental turning movement when either of the corners of the stop is projected above the upper face of the plate 14.

In the use of the device and assuming that a board of two inches in thickness is to be sawed from a log and with the pointer of the frame arranged at zero, the operator proceeds by first operating handle 37 to dis-

engage the pawl 28 from the toothed wheel. When this is done the operator proceeds to swing or turn the frame until the pointer thereof coincides with the division on the scale indicating two inches after which handle 37 is moved to effect engagement between the pawl 28 and wheel 22. At this time stop 16 is adjusted so that an end thereof will intercept the frame when the same returns to its initial position. When the attendant 70 operates the adjusting mechanism of the screws 23, the movement of the screws is transmitted to the frame 25 through the gear wheel 22, and the frame is turned to its initial position, whereupon its movement is so 75 intercepted by the stop 16. At this time the screws 23 have moved the knees 13 for a distance of two inches. It will be obvious that a procedure corresponding to that just described is followed when setting the mechanism to cut a board less or greater than two inches, or to approximately four inches. When it is desired to provide a cut of more 80 than four inches, the operator manipulates the frame to complete one revolution around the scale and to the division thereon indicating the number of inches above four. If it were required to cut a log of six inches in thickness, the operator would manipulate the frame to complete one revolution of the scale 85 and would continue the turning movement of the frame until the indicator coincided with the two inch division of the scale.

It is to be noted that when the frame 25 is manipulated to move in a contra-clockwise 100 direction away from the projecting end of the stop 16, the said frame operates to depress the said projecting end by overriding the same in returning to initial position after moving completely around the scale, so that 105 when the frame is moved in a clockwise direction by the action of the setting mechanism, it operates in passing over the stop to depress the corner on the left thereof, whereby the corner on the right is raised and in 110 position to intercept the frame when the same returns to its initial zero position. In this way the stop operates automatically to intercept the frame on all cuts to be made between one and eight inches. The frame 115 25 is enabled to ride over the stop 16 after a complete revolution of the latter on the shaft 5, because the stop 16 is wider than the frame, and because its upper edge is concave.

Although we have shown the device of the present invention operable automatically to regulate cuts from one to eight inches inclusive, nevertheless, the parts may be so proportioned with respect to any of the prevailing constructions in saw mill carriages as to readily operate with these.

Although we have shown and described one embodiment of our invention, it is to be understood that the same is susceptible of 130

various changes; and we reserve the right to employ such as may come within the scope of the appended claims.

We claim:

- 5 1. A set works having a stop shaft, a toothed wheel fixedly secured to the said shaft, a stationary plate surrounding the shaft, a radially disposed frame rotatably mounted on the shaft and adapted to be moved manually in one direction, means carried by the frame and adjustable into engagement with the toothed wheel for causing the frame to move with the stop shaft in an opposite direction, an oscillating stop connected to the plate and having two oppositely disposed portions respectively adapted to be alternately projected into the path of movement of the frame, one of said portions being adapted to intercept the frame 45 when the same is moved angularly in one direction and for a predetermined distance by the shaft, said portion being further adapted to yield under pressure of the frame when the same is moved manually and in another direction and for a distance of not less than 360°, and means for yieldingly holding the stop against return movement when the same is moved in one direction by the action of the frame.
- 10 2. A set works having a stop shaft, a toothed wheel fixedly secured to the said shaft, a stationary plate surrounding the shaft, a radially disposed frame rotatably mounted on the shaft and adapted to be moved manually in one direction, means carried by the frame and adjustable into engagement with the toothed wheel for causing 50 the frame to move with the stop shaft in an opposite direction, an oscillating stop connected to the plate and having two oppositely disposed portions respectively adapted to be alternately projected into the path of movement of the frame, one of said portions being adapted to intercept the frame when the same is moved angularly in one direction and for a predetermined distance by the shaft, said portion being further adapted to yield under pressure of the frame when the same is moved manually and in another direction and for a distance of not less than 360°.
- 15 3. A set works having a stop shaft, a toothed wheel fixedly secured to the said shaft, a stationary plate surrounding the shaft, a radially disposed frame rotatably mounted on the shaft and adapted to be moved manually in one direction, means carried by the frame and adjustable into engagement with the toothed wheel for causing 55 the frame to move with the stop shaft in an opposite direction, an oscillating stop connected to the plate and having two oppositely disposed portions respectively adapted to be alternately projected into the path of movement of the frame, one of said portions being adapted to intercept the frame when the same is moved angularly in one direction and for a predetermined distance by the shaft, said portion being further adapted to yield under pressure of the frame when the same is moved manually and in another direction and for a distance of not less than 360°, and means for yieldingly holding the stop against return movement when the same is moved in one direction by the action of the frame.
